UNITED STATES PATENT OFFICE.

IRVIN P. DOOLITTLE, OF TORONTO, CANADA, ASSIGNOR OF ONE-HALF TO
EDWARD L. PARKER AND WILLIAM W. PIERCE, OF BUFFALO, NEW
YORK.

DESIGN FOR A GARMENT-HOOK.

SPECIFICATION forming part of Design No. 30,610, dated April 25, 1899.

Application filed March 25, 1899. Serial No. 710,506. Term of patent 14 years.

To all whom it may concern:

Be it known that I, IRVIN P. DOOLITTLE, a citizen of the United States, residing at Toronto, in the county of York, in the Province of Ontario, Canada, have invented and produced a new and original Design for Hooks, of which the following is a specification, reference being had to the accompanying drawings, forming a part thereof.

10 This design relates to the shape or configuration of a hook intended more especially for use as a member of a garment-fastening.

In the accompanying drawings, Figure 1 is a plan view of a hook embodying my design. 15 Fig. 2 is a side or edge view of the same.

Like letters of reference refer to like parts in both figures.

The leading feature of my design consists of the shape or configuration substantially as 20 shown in the drawings, which shape comprises

the straight transverse bar *a*, the short bars *a'* *a'*, arranged parallel with the bar *a* and connected therewith by bends *a*² and extending inwardly to a point opposite the middle of the long bar *a*, and two substantially straight 25 bars *b*, extending laterally from the inner portions of the short bars *a'* and terminating in hooks *b'*. These laterally-extending bars are arranged side by side and at right angles to the short bars *a'*.

30 What I claim is—

The design for a garment-hook, substantially as herein shown and described.

Witness my hand this 23d day of March, 1899.

IRVIN P. DOOLITTLE.
